UNITED STATES PATENT OFFICE.

OTTO C. OEHLER, OF ST. LOUIS, MISSOURI.

BRICK-MASON'S TOOL.

Application filed October 22, 1925. Serial No. 64,151.

To all whom it may concern:

Be it known that I, Otto C. Oehler, a citizen of the United States, residing at St. Louis, Missouri, have invented a certain new and useful Improvement in Brick-Masons' Tools, of which the following is a full, clear, and exact description, such as will enable others skilled in the art to which it appertains to make and use the same.

10 This invention relates to a tool that is adapted to be used by a brick mason for raking out the mortar joints of a brick structure, so as to prepare said joints for tuck-pointing or for producing recessed joints.

15 One object of my invention is to provide a tool of the character referred to that is equipped with an adjustable raking device which can be adjusted easily to vary the depth of the raked joint.

20 Another object is to provide a compact tool of the character referred to that is inexpensive to manufacture and of such construction that the portions of same which engage the brick during the raking operation will not wear out quickly. Other objects and desirable features of my invention will be hereinafter pointed out.

25 Figure 1 of the drawings is a longitudinal sectional view of a tool constructed in accordance with my invention, illustrating the method of using the tool to rake out a horizontal mortar joint of a brick structure.

Figure 2 is an edge view of said tool.

30 Figure 3 is a top plan view of the tool, illustrating how the smoothing portion on the handle of the tool is used to produce a recessed joint; and

Figure 4 is a perspective view, illustrating the method of using the tool.

35 Referring to the drawings, which illustrate the preferred form of my invention, A designates the handle of the tool which is preferably of plate-like form, B designates a pair of arms that project forwardly from said handle, C designates a cross piece or brace attached to the arms B intermediate the ends of same, and D designates a raking device adjustably mounted on said cross piece C and provided with a head 1 that is located beyond the ends or terminal portions of the arms B. To use the tool to rake out the horizontal joint of a brick structure the operator grasps the handle A of the tool in one hand, then arranges the terminal ends of the arms B in engagement with the two courses of brick above and below the

joint that is to be raked, as shown in Figure 4, and thereafter drags the tool longitudinally of the joint over the outer faces of the courses of brick lying above and below the joint so as to cause the raking device D to remove some of the mortar from between said courses, and thus produce what is commonly referred to as a "raked joint."

If the joint is to be tuck-pointed the raking

device D is set so that the head 1 of same is positioned a considerable distance beyond the terminal ends of the arms B, so as to produce a relatively deep joint. If a recessed joint is to be formed the raking de-

vice D is set so that the head 1 of same is positioned only a relatively slight distance beyond the terminal ends of the arms B. In producing a recessed joint it is necessary to smooth out the mortar of the joint after the raking operation, and in order that this operation may be performed with the same tool which is used to rake out the joint, I pro-

vide the handle A of the tool with a smoothing portion E that is used by turning the tool end for end, then introducing the smoothing portion E of same into the raked joint, as shown in Figure 3, and thereafter moving the tool longitudinally of the joint so as to cause the edge of the smoothing portion E to smooth down the mortar and make it even. The arms B are preferably provided with enlarged terminal portions 2, and in order to prevent said terminal portions from wearing out rapidly, I equip them with

30 inserts 3 formed from metal that has great wear resisting properties. Generally, the handle A, the arms B and the cross piece C of the tool will be constructed from a casting of aluminum or other light-weight metal,

35 and the inserts 3 in the terminal portions 2 of the arms B will be formed from coiled steel springs that are imbedded in said terminal portions, during the operation of casting the same. The smoothing portion E is also

40 integrally connected to the handle A and the edge of said smoothing portion is curved or convexed slightly so as to facilitate the operation of smoothing down the mortar when the tool is being used to produce a recessed joint.

45 The raking device D can be adjustably mounted on the tool in various ways without departing from the spirit of my in-

50 vention, but I prefer to provide said raking device with an externally screw-threaded portion 4 that passes through an internally

55 screw-threaded hole in the cross piece C and

60 65 70 75 80 85 90 95 100 105 110

which carries a jam nut 5 that is used to lock said raking device in adjusted position, said jam nut being held against accidental movement by a spring lock washer 6 that is interposed between the jam nut 5 and the cross piece C into which the raking device is screwed.

A tool of the construction above described makes it possible to produce uniform raked joints in a brick structure; it can be adjusted quickly and easily to produce shallow joints or deep joints; it can be used to prepare mortar joints for tuck-pointing or to produce recessed joints; it is compact enough and light enough to enable it to be carried conveniently in a brick mason's pocket; it can be manufactured and sold at a low cost due to its simple design, and as the terminal portions of the arms B are provided with inserts of steel or other hard material, long usage does not materially interfere with the operation of the tool.

Having thus described my invention, what I claim as new and desire to secure by Letters Patent is:

1. A brick mason's tool, comprising a handle provided with arms whose ends are adapted to be arranged in engagement with a brick structure at opposite sides of a mortar joint in said structure, and an adjustable raking device positioned between said arms and projecting forwardly beyond the ends of same for removing some of the mortar from said joint when the tool is moved lengthwise of the joint.

2. A brick mason's tool, comprising a handle provided with arms whose ends are adapted to be arranged in engagement with a brick structure at opposite sides of a mortar joint in said structure, an adjustable raking device positioned between said arms and projecting forwardly beyond the ends of same for removing some of the mortar

from said joint when the tool is moved lengthwise of the joint, and a portion on 45 said tool that is adapted to be used to smooth down the mortar in the joint after the joint has been raked.

3. A brick mason's tool, comprising a handle, a pair of spaced arms attached to said handle, large terminal portions on said arms provided with inserts formed of material that has great wear-resisting properties, and an adjustable joint raking device arranged between said arms. 50 55

4. A brick mason's tool consisting of a cast metal handle provided at one edge with an integral smoothing portion and at its opposite edge with integral arms arranged in spaced relation, a cross piece or brace integrally attached to said arms intermediate the ends of same, a joint raking device provided with a screw-threaded portion that passes through a screw-threaded hole in said cross piece, and a jam nut arranged on said 60 screw-threaded portion above said cross piece for holding said raking device in adjusted position. 65

5. A brick mason's tool consisting of a cast metal handle provided at one edge with 70 an integral smoothing portion and at its opposite edge with integral arms arranged in spaced relation, a cross piece or brace integrally attached to said arms intermediate the ends of same, a joint raking device provided with a screw-threaded portion that passes through a screw-threaded hole in said cross piece, a jam nut arranged on said 75 screw-threaded portion above said cross piece, a lock washer interposed between said jam nut and cross piece, and enlarged terminal portions on said arms provided with inserts formed by coiled steel springs that are imbedded in said terminal portions. 80

OTTO C. OEHLER.
